UNITED STATES PATENT OFFICE

FRANK R. FAGEOL AND WILLIAM B. FAGEOL, OF KENT, OHIO, ASSIGNEES TO TWIN COACH COMPANY, OF KENT, OHIO, A CORPORATION OF DELAWARE

DESIGN FOR A MOTOR VEHICLE

Application filed May 7, 1931. Serial No. 39,755. Term of patent 14 years.

To all whom it may concern:

Be it known that we, FRANK R. FAGEOL and WILLIAM B. FAGEOL, citizens of the United States, residing at Kent, in the county of Portage and State of Ohio, have invented a new, original, and ornamental Design for Motor Vehicle, of which the following is a specification, reference being had to the accompanying drawings, forming a part thereof.

We claim:

The ornamental design for a motor vehicle substantially as shown.

FRANK R. FAGEOL.
WILLIAM B. FAGEOL.
